J. C. BEATTIE,
WATER PURIFYING SYSTEM FOR STEAM BOILERS.
APPLICATION FILED NOV. 26, 1919.

1,372,393.

Patented Mar. 22, 1921.

UNITED STATES PATENT OFFICE.

JOHN C. BEATTIE, OF LONDON, ONTARIO, CANADA, ASSIGNOR OF ONE-HALF TO M.
WHITE & SON, OF LONDON, ONTARIO, CANADA.

WATER-PURIFYING SYSTEM FOR STEAM-BOILERS.

1,372,393.

Specification of Letters Patent. Patented Mar. 22, 1921.

Application filed November 26, 1919. Serial No. 340,828.

To all whom it may concern:

Be it known that I, JOHN C. BEATTIE, of the city of London, in the county of Middlesex, Province of Ontario, Canada, have invented certain new and useful Improvements in Water-Purifying Systems for Steam-Boilers, of which the following is a specification.

In districts where soft water is not available, much trouble is experienced from 10 deposits of sediment and scale in steam boilers, and my object is to devise an attachment which may be made to existing boilers without alterations thereto to effect the precipitation of sediment and scale from the feed water before passing to the boiler.

I attain my object by means of constructions hereinafter described and illustrated in the accompanying drawings in which—
20 Figure 1 is a plan view of the water purifying system applied to a steam boiler; and Fig. 2 a front elevation of the same.

In the drawings like numerals of reference indicate corresponding parts in the 25 different figures.

1 represents part of the combustion chamber of a steam boiler and 2 the feed water well to which water of condensation is led and to which will lead wherever possible 30 a water supply pipe 3 conveying water under pressure from any suitable supply such as a city waterworks system. 4 indicates suitable means for drawing the water from the well and forcing it into the boiler 35 under pressure, such, for example, as an ordinary inspirator or injector. 5 is the steam supply pipe of the inspirator and 6 the suction pipe. 7 is the outlet pipe of the inspirator, which is connected with 40 one end of the pipe 8. This pipe 8 is led through a part of the combustion chamber of the steam boiler. In its preferred form this water heating pipe is U-shaped, as shown particularly in Fig. 1. The other 45 end of the pipe 8 is connected with one end of the settling tank 9 by means of the pipe 10. To the other end of the settling tank is connected the pipe 11, through which the purified feed water may pass to the boiler.

50 From the above description it will be seen that feed water above boiler pressure is passed through the water heating pipe 8, thence through the settling tank 9 and thence to the boiler. In the settling tank

sediment and scale which would otherwise be deposited in the boiler settles out and may be withdrawn through the blow-off valves 12.

To provide for the proper operation of the system, other features must be embodied in the system. As an inspirator will not work satisfactorily if the boiler pressure is below a certain limit, which limit is usually below the pressure obtainable from a city water supply system, I provide the pipe 13 which connects the water supply pipe 3 with the pipe 7. Between the inspirator and the connection of the pipe 13 I provide the controlling valve 14. When this valve is closed and the valve 15 in the pipe 13 open, water from the pipe 3 may pass directly through the water heating pipe 8 without going through the inspirator. To prevent any back flow I provide a check valve 16 in the pipe 7 between its connection with the pipe 13 and its connection with the pipe 8. In the pipe 11 leading from the settling tank to the boiler a control valve 17 is provided. If for any reason the water heating pipe, 70 the settling tank or other part of the apparatus is out of commission or needing repairs, the valves 14 and 17 may be closed and the boiler fed by any of the ordinary supply means, which will not usually be interfered with when my system is installed. 75

A pipe 18 provided with a blow-off valve 19 preferably leads from the pipe 11, through which any sediment collecting there may be blown out.

The settling tank 9 is divided into two 80 chambers by two overlapping substantially upright partitions 20, one extending from the bottom of the tank nearly to the top and the other extending from the top nearly to the bottom. The blow-off valves 12 are 85 located one below each of these chambers. With this arrangement a minimum of agitation is caused to the water in the settling tank by the entry and outlet of the feed water and a maximum of settlement is thus obtained.

It will be found that with the system described the objects of my invention as set forth in the preamble to this specification are readily attained.

A further result attained is that a considerable economy in fuel results owing to the water surfaces of the boiler being kept free

from scale and sediment which obstruct the free passage of heat from the hot gases to the water within the boiler.

What I claim as my invention is:—

- 5 1. The combination with a boiler and furnace of a water heating pipe located within the combustion chamber of the furnace, but having its ends extended through the furnace wall; an inspirator adapted for connection with the steam space of the boiler and a source of water supply; a pipe leading from the outlet of the inspirator to one end of the water heating pipe; a settling tank; a pipe connected with the other end 10 of the water heating pipe and the settling tank; a pipe leading from the upper part of the settling tank to the boiler; and a blow-off valve at the bottom of the settling tank.
- 15 2. A water purifying system constructed as set forth in claim 1 provided with an auxiliary pipe for the supply of water under pressure connected to the pipe leading from the inspirator to the water heating pipe;
- 20 25 a controlling valve in said water supply pipe; a controlling valve in the pipe from the inspirator between the inspirator and

the connection with the auxiliary water supply pipe; and a check valve in the pipe from the inspirator between the connection of the auxiliary water supply pipe and the water heating pipe.

3. A water purifying system constructed as set forth in claim 1 provided with an auxiliary pipe for the supply of water under pressure connected to the pipe leading from the inspirator to the water heating pipe; a controlling valve in said water supply pipe; a controlling valve in the pipe from the inspirator between the inspirator and the connection with the auxiliary water supply pipe; and a check valve in the pipe from the inspirator between the connection of the auxiliary water supply pipe and the water heating pipe; a controlling valve in the pipe leading from the tank to the boiler; and a blow-off valve in said pipe between the controlling valve and the boiler.

Signed at the city of London, this fifteenth day of November, 1919.

J. C. BEATTIE.
